HEAT-TREATING FURNACE

Frederick A. Endress, Detroit, Mich., assignor to
Tuff-Hard Corporation, Detroit, Mich., a corporation of Michigan

Application December 2, 1941, Serial No. 421,362

1 Claim. (Cl. 263—43)

My invention relates to furnaces, and more particularly to means and a method of controlling the operation of a furnace in preparing same for subsequently heat treating a material. Preferably the present invention is applicable to a furnace having a retort chamber for receiving the material to be treated by radiant heat, the retort chamber being raised to the desired relatively high temperatures by burning a combustible fuel in said retort chamber, and it is more especially useful for processing ferrous materials as described and claimed in my copending application for patent, Ser. No. 370,577, filed December 18, 1940, entitled "Process for heat treating steel."

In heat treating, and especially heat treating materials by a process requiring very high temperatures, it is noted that these high retort temperatures can only be had by means of a flame playing directly in the retort chamber. The presence of oxygen in the retort chamber when the material is being processed therein is injurious to the work, as it causes oxidation and burning of the material or work. It is necessary, when employing high temperatures to remove the products of combustion and to introduce an atmosphere in said retort chamber suitable for use in subsequent operations of the process, the preferred process utilizing heat stored in the retort chamber. Furnaces of the muffle type are unsuitable for use in a process employing these excessively high temperatures as it is impossible to obtain such temperatures in the retort chamber and therefore direct heating of the retort chamber is necessary. The products of combustion, if left in the retort chamber, are injurious to the work and also prevent one from preparing the proper atmosphere around the work being processed in order to eliminate oxidation and burning of the work and the formation of scale.

An object of my present invention is to process material in a gas fired furnace or other similar furnaces having a retort chamber, in which a combustible fuel has been burned to heat the chamber to the temperature required, and to introduce a gas atmosphere into said chamber which scavenges the chamber of the products of combustion, and which then provides an atmosphere therein having a predetermined analysis and pressure suitable for use in subsequent operations of the furnace in processing the material which is to be treated therein.

A further object of my invention is to accomplish these results automatically, preferably by providing means automatically operable to sub-

ject the furnace to a plurality of successive operations, which scavenges the furnace retort chamber of the products of combustion and prepares an atmosphere therein of a predetermined analysis and pressure suitable for use in subsequent operations of the furnace in processing the material which is to be heat treated therein.

Obviously, there may be many means for controlling these operations to which the furnace is subjected, and for purposes of illustration I have chosen to illustrate some of the more practical means for accomplishing the desired result. Obviously, the principles of my invention can be carried out by hand and therefore my invention may be defined by method or process claims as well as by claims broadly and specifically directed to the means for carrying out my novel process or method.

For a more detailed understanding of my invention reference may be had to the accompanying drawings and description defining preferred embodiments of my invention, in which like characters refer to like parts throughout the several views, and in which:

25 Fig. 1 is an elevational view of a preferred embodiment of my invention, illustrating the furnace control means somewhat diagrammatically, Fig. 2 is a diagrammatic view of a modified furnace control means, 30 Fig. 3 is a detail sectional view of a furnace found to be suitable for my purpose and applicable for my method of operation,

Fig. 4 is an illustration of a modified construction, and

35 Fig. 5 is a time diagram of the successive steps in my process of preparing the retort chamber for carrying out subsequent operations of the heat treating process.

The furnace "A" illustrated herein provides a 40 retort chamber 10 into which a supply of combustible fuel mixture is fed by means of a suitable induction system 11 including a main fuel supply line 12 controlled by a main "shut off" valve 13, an air mixing device 14 and a control valve 15, from which lead the conduits or pipes 16 which are preferably divided to form a pair of branch conduits 16a and 16b leading to the furnace fuel mixture intake port openings 17. Preferably the conduits 16a and 16b terminate in fuel 45 nozzles 18 which direct the fuel mixture into the furnace retort chamber 10, where same is ignited and burned to heat the furnace, said heat being customarily stored in the retort chamber walls, the stored heat being subsequently used to process the material being treated.

The furnace is preferably provided with a pair of vent outlet openings 20 each of which carry valve 21 which are operable to close these openings when desired. The furnace retort chamber is also provided with an inlet opening 22 connected with a pipe 23 through which a gas of a predetermined analysis and pressure may be introduced into the retort chamber to flush same, and scavenge the products of combustion from said chamber. The furnace is provided with a door 25 which may be opened so that access may be had to the interior of the retort chamber. Valve 27 is incorporated with the pipe or conduit 23 to control the flow of gas therethrough. If desired the second induction system may exhaust into conduits 16, and thus the flushing gas is introduced from pipe or conduit 23a to branched pipes 16a and 16b in the furnace as shown in Fig. 4.

In heat treating material in this furnace which may be classified broadly as of the gas fired type, the furnace is heated to a relatively high temperature, and the direct flame in the retort chamber is then cut off before the material being treated is placed within the retort chamber, said material being brought to temperature by the stored radiant heat.

My present invention is directed to the means and method for preparing the furnace retort chamber for subsequent operations in the heat treatment of material, particularly ferrous materials. This is accomplished by first burning a combustible fuel within the furnace retort chamber to bring same up to temperature, and when the furnace is at temperature to "cut off" the supply of combustible fuel being fed into the retort chamber. Next the valve 27 is opened wide and the flushing gas of predetermined analysis, suitable for subsequent heat treatment of the material being processed, is injected into the retort chamber to scavenge said chamber of the products of combustion which remain therein, after turning off the fuel supply. The products of combustion are thus eliminated from the chamber through the vent outlet openings 20 as the valves controlling same are open. After completely scavenging the furnace retort chamber of the products of combustion which takes only a short time, the valves or closures 21 are closed thus permitting the pressure within the retort chamber to approach or attain the same value as the pressure of the gas within the second induction system 23. The next step is to maintain the atmosphere of predetermined analysis, and to adjust the pressure thereof so that the atmosphere is suitable for subsequent processing of the material being treated. This is preferably accomplished by using gas of the desired analysis and regulating the pressure of same by means of a regulable valve 27. Preferably the furnace retort chamber is sealed as far as is practical and the regulable valve 27 is designed to admit such gases as is needed to maintain an atmosphere within the retort chamber of the desired analysis and pressure.

It will be apparent that the various controls for preparing this furnace retort chamber for subsequent operations in heat treating material may be operated manually if so desired. However, these various operations must be carried out very quickly, and in order to maintain efficient operation of the furnace, it is desirable to incorporate an automatic means for controlling these successive operations of the furnace, and there-

fore, in Fig. 1, I have illustrated one practical solution for automatically controlling the various steps in my new method of furnace operation.

I have provided a master control device "B" which may be driven from any suitable source of power, and comprise principally a drive shaft 30 carrying a member 31 that carries a contact arm 32, member 31 being electrically connected in any suitable manner to a source of electric current supply 33 through an electrical connection 34, which includes a brush 35 and switch 36 which may be opened to cut the whole control system "off." Preferably, suitable means are provided for controlling the operation of member 31 so that same will, when put in operation, have only one complete revolution. This may be accomplished by means of any suitable mechanical or electrical mechanism which is well known in the art, and which is here designated as a whole by reference character 37, same being operated by a lever 37a. This mechanism preferably includes a brake 38 operable to engage the brake drum 39 carried by member 31 so as to stop the rotation of member 31 when it has completed one revolution. The "at rest" position is identified by character 48 and I have illustrated the contact arm 32 in the "at rest" position by dotted lines in Fig. 1.

As the mechanism is placed in timed operation, the contact arm 32 first engages the stationary contact ring 41 which ring is connected through the electric connection 42 to a solenoid 43 and these by connection 44 to the source of electric power 33. The solenoid 43 operates the plunger 45 which is connected with an actuating arm 46 of the valve 15. This valve 15 has been previously moved to the "on" position so that combustible fuel is fed to the furnace to be burned for heating same, this valve being preferably turned "off" and "on" by a manually operated arm 47. When the contact arm 32 contacts the contact ring 41 the solenoid 43 is energized to retract the plunger 45 and thus move the arm 46 to the "off" position thus closing the valve 15 and shutting off the supply of combustible fuel which is being fed to the furnace retort chamber 10.

As the control mechanism continues its operation the contact arm 32 next engages the contact ring 50 which is connected with leads 51 and 52 leading to the solenoids 53 and 54 respectively. Connections 55 and 56 connect the other terminals of the solenoids with the source of electric power 33. Thus, after the fuel supply has been cut off the solenoids 53 and 54 are energized to retract the plunger 57, which is connected with the arm 58 of the regulable valve 27. Thus the arm 58 is moved from the "off" position to a "full on" position, and the flushing gas of predetermined analysis and pressure is thus allowed to rush through the pipe 23 or 23a through the intake 22 or 17 into the furnace retort chamber 10. This gas flushes the chamber and scavenges all of the products of combustion then remaining in the chamber through the vent outlet openings 20. It will be apparent that in a short while the retort chamber is completely cleared of objectionable gases and vapors comprising the products of combustion, and my control is designed so that while valve 27 is "full on" the valves or closures 21 controlling the vent outlet openings are actuated to close. It will be seen that as the contact arm 32 is rotated it will next engage the contact ring 60 which is connected with the electrical connection 61 leading to the solenoid 62,

the other terminal of the solenoid being connected with an electrical connection 63 leading to the source of electric power 33. As the solenoid 62 is energized it will retract the plunger 64 which is connected with an arm 65 and links 66 with the valves or closure members 21.

The rotating contacting arm 32 will next pass beyond the end of the contact ring 50 and disconnect the solenoids 53 and 54 from the source of electrical power through the ring 50. Preferably the plunger 57 has associated therewith some suitable resilient or spring return means tending to move the valve arm 58 to a closed or "off" position. But before the contact arm leaves the contact ring 50 it is arranged to engage the contact ring 70 which is connected by an electrical connection 71 with line 52 connected with one terminal of the solenoid 54 and thus when the contact arm leaves contact ring 50 it is only the solenoid 53 which is de-energized and thus the operation of solenoid 54 alone moves the plunger 57 so as to move the valve arm 58 to the "part on" position 72 which has been predetermined in accordance with predetermined requisites. At "part on" position the valve 27 is constructed to supply a lesser amount of this flushing gas of predetermined analysis to the furnace retort chamber and preferably at a lesser pressure, which pressure is predetermined to supply just the proper amount of this gas of predetermined analysis to the furnace retort chamber for use in subsequent operations of the furnace in heat treating the desired material.

The time element for flushing the chamber and for introducing gas thereto at a reduced pressure may be varied by lengthening or shortening the contact rings 50 and 70 as indicated by the dotted lines 50a and 70a in Fig. 1. Obviously the means for varying the time intervals is preferably manually operated and the constructional details are somewhat dependent on the type of control employed.

As the contact arm continues its rotation it will complete one revolution when it reaches the "at rest" position 40. In the "at rest" position, said contact arm moves out of contact with the contact rings 41 and 60, thus de-energizing the solenoids 43 and 62 respectively. The plungers 45 and 64 are preferably constructed so that same will not be spring returned as it is desired that the fuel valve 15 remain "off" and the valves 21 remain closed when the contact arm is positioned at the "at rest" position. The valve 27 is, however, preferably spring closed when the solenoids 53 and 54 are de-energized although if desired, the plunger 57 may be constructed without a spring return if it is desired to continue feeding in this gas through line 23 for maintaining the proper atmosphere in the retort chamber during subsequent operations of the furnace in heat treating the selected material. Preferably, however, the contact ring 70 is extended as at 70b and the arm 32 is still in contact therewith at the "at rest" position so that the valve 27 will be maintained in the "part on" position. Preferably line 56 embodies a switch 56a having a switch arm 56b connected with arm 46 of the fuel valve 15 so that when the fuel is turned "on" the switch 56a will be turned "off," but turned "on" again as soon as valve 15 is turned "off."

The above control means will automatically control these successive operations consisting in first shutting off the supply of combustible fuel, then flushing the chamber, next closing the vent openings, and finally varying the regulable valve

27 for continuing the introduction of the flushing gas of a predetermined analysis and at a predetermined reduced pressure until such time as the fuel is again turned "on" for operation of another cycle.

In opening the furnace door 25, it will be apparent that much of the atmosphere within the chamber might be lost but I find it quite satisfactory to provide means associated with the door so that when same is opened the solenoid 53 will be energized to momentarily turn the gas valve 27 full on. This is preferably accomplished by means of a plunger 80 mounted in the furnace which is urged outwardly by means of a spring 81 but held in a retractive position by the door when same is closed. As the door is opened, the plunger 80 is urged outwardly of the furnace and is connected with an arm 82 which is thus moved into engagement with a contact 83. Contact 83 is connected by an electrical connection 84 with one terminal of solenoid 53 while the arm 82 is connected with the source of electrical power 33 by means of an electrical connection 85 and the lead 34. Thus when the door is closed after placing the material to be heat treated in the retort chamber second induction system is partly cut "off" as the solenoid 53 is de-energized, valve 27 remaining "part on" because contact arm 32 is still in contact with contact ring 70 at 70b.

In Fig. 2, I have illustrated a modified construction which comprises a mechanical control device suitable for controlling the combustible fuel valve 15, gas valve 27 and the valves or closures 21. This modified structure provides a motor "M" connected to drive a cam C through a speed reducer 90 by means of suitable bevelled gears 91, a trip mechanism 92 including a brake shoe 93 of standard construction is associated with the cam C to stop same when it has completed one revolution, said mechanism being constructed to also cut off the motor "M" and this mechanism can be again put into operation by moving the arm 94. Since this type of mechanism is well known in the art it is not deemed necessary to illustrate or describe the details of the structure. The cam C carries an actuating cam portion 95 which is engaged by the plunger 96 as the roller 97 carried by said plunger 96 rides on the cam portion 95. It will open communication between the hydraulic lines 97a through the valve 98 and thus function to operate the valve 15 in any suitable manner so as to close said valve. Likewise, as the cam is rotated in the direction of arrow 99, the cam portion 100 is brought into engagement with roller 101 carried by plunger 102, whereby to operate valve 103 to connect the hydraulic lines 104 in such a way as to operate the atmosphere control valve 27, cam portion 100 maintaining said valve 27 in a "full" position. Next the cam portion 105 is moved into contact with roller 106 carried by plunger 107 and thus the valve 108 is operated to place the hydraulic lines 109 in communication so as to operate a suitable mechanism for closing the chamber outlet valves 21. Subsequent to the closing of the chamber outlet valves 21, the roller 101 leaves the cam portion 100 and rides on the cam portion 110 so as to move the valve 103 to connect the hydraulic line 111 whereby to actuate the valve 27 in a suitable manner to move same to "part on" position, and to maintain the valve 27 in a "part on" position in the "at rest" position of said mechanism.

It will thus be seen that the mechanical control means illustrated in Fig. 2 can be con-

structed and arranged for actuating valves 15, 27 and 21 in a manner similar to the electrical control means illustrated in Fig. 1. If desired, suitable hydraulic lines 112 may be connected with lines 104 and with a suitable valve which is actuated by opening the furnace door 25 so as to momentarily open valve 27 to a "full on" position when the furnace door is open.

It will be understood that the time element involved in completing the cycle of operations necessary in preparing the furnace retort chamber for subsequent operations in the heat treatment of ferrous alloys or other material may be conveniently varied, the regulable valve 27 may be constructed and arranged so same can be adjusted within limits, so as to make it possible to very accurately control the atmosphere within the furnace when heat treating said material. It will be obvious that the incorporation of an automatic control makes the operation of the furnace substantially "fool proof" and this control means and method is particularly important when heat treating materials subjected to a high heat in a controlled atmosphere in the process of heat treating same, especially when employing a process embodying a positive time and temperature control.

The principles of my invention are of particular utility in connection with the heat treatment of materials in a furnace of the gas fire type, and the operation of my process for preparing and maintaining an atmosphere of predetermined analysis and pressure in a furnace of this type is found to be of great importance and utility.

In the treatment of some materials it is desired to employ an inert atmosphere in the furnace retort chamber such as N₂ gas and the valve 27 is capable of controlling the pressure of this

inert gas. In other applications it is found desirable to employ a carburizing gas atmosphere such as CO or other carburizing gases, and thus the mechanism herein illustrated and described is applicable for supplying and maintaining by means of the regulable valve 27 such an atmosphere in the furnace retort chamber.

The mechanism and method described herein may be manually controlled but is preferably automatically controlled by some suitable electrical or mechanical means such as is typified by the constructions illustrated in the accompanying drawings.

It will be apparent to those skilled in the art to which my invention pertains, that various modifications and changes may be made therein without departing from the spirit of my invention or from the scope of the appended claim.

I claim:

The combination with a heat treating furnace having a retort chamber adapted to receive material to be treated, and a door opening into said chamber, of means for introducing a heating medium into said chamber, valve means for controlling the flow of said heating medium through said introducing means, means for introducing a non-oxidizing gas into said chamber, a second valve means for controlling the flow of said gas through the second mentioned introducing means, actuating means connected to both said valve means, and a common control means for said actuating means operable to effect actuation of said valve means in timed relation to each other, said control means being so constructed and arranged as to cause closing of the first mentioned valve means as a condition precedent to the opening of said second valve.

FREDERICK A. ENDRESS.
